ELECTROLYTIC CONDENSER

Victor F. Zahodiakin, Cincinnati, Ohio

Application July 14, 1934, Serial No. 735,209

16 Claims. (Cl. 175—315)

This invention relates to improvements in electrolytic condensers.

It is the object of this invention to provide a durable, inexpensive and easily manufactured 5 electrolytic condenser for use on radios or the like.

It is another object of this invention to provide a condenser of this character, the principal or base parts of which may be manufactured 10 of any insulating material, that is to say, material which is ineffective for the purposes of electrolytic action or conductivity. This is highly advantageous since the parts ordinarily used for the purposes of electrolytic action are usually 15 expensive. In other words, inexpensive material, such as glass, composition, paper, etc., may be used in the fabrication of these base parts of the condenser and the amount of material used in the condenser having the requisite qualities 20 may thus be reduced to a minimum.

Accordingly, it is intended that the present invention in its first aspect, resides in the feature of coating these inexpensive base materials with a film of material having the qualities necessary 25 for the use intended.

The capacity of electrolytic condensers is proportionate to the effective area of the anode. Therefore, the present improvement will provide a maximum area at low cost since the base part 30 can be molded, formed or cast to include a multiplicity of corrugations or fins and the amount of material required for the part may be entirely disregarded in estimating cost. It is pointed out that the materials, such as aluminum, 35 ordinarily used for these parts, are quite expensive and the fabrication of these parts of the materials ordinarily used is extremely difficult and therefore expensive.

It is a further object of this invention to provide 40 a condenser which does not require expensive forming machinery in its manufacture, the container including the anode surface and having the anode contact terminal cast therein and accordingly being readily made proof against 45 leakage of the electrolyte therefrom.

It is a still further object of this invention to provide a condenser container including the anode formed on its inner surface, which container is readily formed of heavy, rigid structure, that is to say, can have considerable mass 50 because of the use of inexpensive base material. Accordingly, the container will be more rigid for the purpose of positive and rigid attachment of parts thereto, such as the closure, thereby entirely eliminating the possibility of leaks. 55

The conventional structure, because of the expense of the material and difficulty of manufacture, is made of extremely thin material which will not permit a firm or rigid attachment of the closure parts thereto. Therefore, it will be 5 apparent that with the use of relatively thin material, the parts will not stand up in the operations of attachment.

It is a still further object of this invention to provide a condenser anode formed by placing a 10 film of material having electrolytic properties, such as aluminum, on the roughened surface of the base material whereby a good bond is procured between the base part and the film and at the same time the effective area of contact is 15 increased due to the roughened surface.

It is a still further object of this invention to provide a condenser, the outer part of which may be formed of some non-corrosive material, such as glass. 20

It is a still further object of this invention to provide a condenser structure which eliminates gas pockets, is not likely to be short-circuited, and eliminates numerous insulators heretofore employed in condensers of this character. 25

Other objects and further advantages will be more fully apparent from a description of the accompanying drawing, in which:

Figure 1 is a side view of the improved condenser. 30

Figure 2 is a sectional view of the condenser taken on line 2—2, Figure 1.

Figure 3 is a sectional view taken on line 3—3, Figure 1, detailing the irregular contour of the inner surface of the container for increased area. 35

Figure 4 is a side view partly in section illustrating a modified form of the condenser.

Figure 5 is a fragmentary side view partly in section showing a modified form of closure cap for the condenser. 40

Referring to the drawing, the condenser includes a container 10. The container 10 carries the anode, this anode being provided in the form of a film or coating 11 on the internal surface of the container. The container body may be 45 formed of any inexpensive insulating material, in this instance being made of glass. The terminal 12 for the anode is cast or molded within the material of the container and has an end internally disposed. The container as initially formed, includes this terminal and the film or coating subsequently applied to the interior thereof, also covers the inner end of the terminal. Since the main or support part only functions as a base or support for the conductive parts of the condenser, 50 55

its main requisite is that it be of insulating material. It is important that the material selected be inexpensive, easily formed and having the proper strength. The material of the film or coating is selected for its electrolytic qualities and for this reason it is preferable to use aluminum.

The film or coating may be secured to the interior of the container by electro-plating processes 10 or by spraying the material thereon in liquid form. For the purpose of increasing the area and providing a good bond between the coating and the base material, the surface of the base material can be prepared by roughening the same 15 either as initially molded or by subsequently sand blasting the same. It will be understood that the roughened surface will provide greater area and this is to be desired for greater capacity of the condenser.

20 It will be noted from Figure 3 that the container walls, particularly the inner wall surface, has greatly increased area due to a multiplicity of corrugations 12^a which greatly extend the wall surface. This corrugated wall because it provides 25 greater external wall surface, has the added function of rapidly dissipating the heat which is generated by the operation of the condenser. It will be observed that a very excellent connection 30 through the anode terminal is obtained by virtue of the fact that the anode terminal extends to the interior of the container and is coated by the anode film.

The cathode of the condenser is indicated at 13 and is in the form of a long tube 14 depending centrally within the container but short of the bottom thereof and submerged in the electrolyte, and a cap portion 15 attached to the upper end of the container and forming a sealed closure therefor. The inner coating or film forming 40 the anode disposed on the internal wall of the container, terminates short of the upper end of the container, as at 16, so as to be entirely free of contact with the cathode.

The cap portion of the cathode may be of any 45 type for a rigid attachment thereto, being either in the form of a clinched cap, as shown in the main view, or a screw cap, as shown in the modified view. A sealing gasket 17 is placed under the cap. It is necessary that there be some outlet 50 for gases generated within the condenser and for this reason the cathode tube is perforated, as at 18, at its upper end, and a valve 19 is fabricated into the cap structure at the upper end of the tube, that is, disposed across the upper end of 55 the tube.

Referring to the drawing, the cap and tube of the cathode can be separate pieces for the purpose of attaching the valve in position. The cap element includes a central aperture 20 aligned 60 with the tube and the tube includes an upper flange 21 for attaching the same to the underside of the cap. The valve is in the form of a rubber disc and is engaged between the flange of the tube and the margin of the cap about the opening 65 thereof.

In view of the fact that it is desirable to permit escape of gas without permitting leakage of the electrolyte from the container, the valve disc is provided with a minute opening which under 70 normal circumstances will not permit leakage of the electrolyte from the container but in case gases are generated in the condenser, the rubber disc will be pressed outwardly, thereby spreading and enlarging the opening and permitting escape 75 of the gases.

The condenser is usually mounted on a panel, indicated at 22. The container may include a screw-threaded boss 23 adapted to traverse an opening 24 in the panel and to be attached therein by means of a nut 25 engaging the underside 5 of the panel and drawing the condenser thereagainst.

For the purpose of completing the circuit, the external surface of the container may be coated or provided with a film 26 of some material which is a conductor of electricity. This coating should extend from the mouth of the container to the boss on the underside of the container for engagement with the panel. A good connection is made from the cathode to this coating by virtue 15 of the attachment of the cap to the container. The cathode parts, including the external film, are preferably formed of copper.

In the operation of the condenser, the current passes into the terminal of the container, through 20 the anode, through the electrolyte, through the cathode tube, through the cap, through the external filming and thence to the panel.

In the modified form shown in Figure 4, a cathode terminal 27 is connected directly to the 25 cap and the external coating or film of the previous form is not used. Also, in this form of the device, the container as initially formed is open at both ends. Accordingly, for the purpose of closing and sealing the lower end, a cap 28 is employed. This cap may be attached by clinching in the same manner as the cap of the cathode. In this form of container, a plurality of radial fins 35 are provided.

The internal coating forming the anode is extended around the lower edge of the container, as indicated at 29, a sufficient distance to make a good contact with the clinched portion of the cap. A sealing gasket 30 is used for sealing the cap against leakage at the lower end.

The cap 28 includes a screw-threaded extension 31 projecting through the opening of the panel and secured by means of a nut 32. Insulators 33 and 34, upper and lower respectively, are provided on each side of the panel between the nut 45 and the condenser cap. The lower insulator is in the form of a washer whereas the upper insulator is cup-shaped and extends up the side of the condenser a sufficient distance for covering the circuit carrying lower cap. In other words, this insulator acts as a shield and has the purpose of preventing physical contact with the current passing through the anode of the condenser.

In the operation of the condenser in this form the current passes into the lower cap to the film 55 or coating of the anode, through the electrolyte, through the cathode tube, and thence from the condenser through terminal 27.

Having described my invention, I claim:

1. In an electrolytic condenser, a closed container formed of insulating material and having an electrolytic solution therein, said container having its inner surface coated with a material forming a filming anode, a terminal fixed in one end of said container and in connection with 60 said coating, the other end of said container including a conductor of electricity insulated from said coating, and a cathode tube extending from said conductor of electricity into said container.

2. An electrolytic condenser, comprising, a container 70 formed of glass and having its internal surface coated with a film of material forming an anode, said container having an electrolyte therein, and a cathode supported in said electrolyte and insulated from said film of material. 75

3. In an electrolytic condenser, a container formed of insulating material and having a roughened inner surface and coated with a material forming an anode, said container having an electrolyte therein, and a cathode in said container insulated from said coating.
4. In an electrolytic condenser, a sealed container formed of glass or the like and having an electrolyte therein and having its inner surface 10 coated with aluminum, a cathode suspended in said electrolyte and insulated from said coating.
5. An electrolytic condenser, comprising, a container formed of insulating material and having a plurality of corrugations in its walls providing increased internal and external area, the inner 15 surface of said container coated with a film of material forming an anode, said container having an electrolyte therein, a cathode mounted in said container, and means for closing said container.
- 20 6. An electrolytic condenser, comprising, a container for an electrolyte formed of insulating material, having a multiplicity of fins formed on its inner surface for providing greater area therefor, said inner surface coated with a film of material 25 forming an anode, and a cathode mounted adjacent said film.
7. An electrolytic condenser, comprising, a casing formed of insulating material and having its inner and outer surfaces coated with a material 30 forming an anode, said casing having an electrolyte therein, a terminal at one end of said casing in engagement with the inner film, and a closure at the other end of said casing having a cathode 35 thereon suspended in said electrolyte, said closure in engagement with the outer film.
8. An electrolytic condenser, comprising, a container formed of insulating material having a coating on its inner wall formed of a material constituting an anode, said container having an electrolyte therein and having a cap closing said 40 open end, a cathode tube suspended from said cap within said container and spaced therefrom, and an electrical connection to said coating at the closed end of said container.
- 45 9. An electrolytic condenser, comprising, a molded container formed of insulating material and having a closed end and having a film of material on its inner surface forming an anode, a terminal molded in said closed end in engagement with said film, and a cathode disposed in 50 said container having an electrical connection thereto, said container having an electrolyte therein.
10. An electrolytic condenser, comprising, a 55 molded container formed of insulating material and having a closed end and having a film of material on its inner surface forming an anode, a terminal molded in said closed end in engagement with said film, and a cathode disposed in said container, the outer surface of said container coated with a film of material capable of conducting electricity, and said cathode in engagement with said film.
- 60 11. In an electrolytic condenser, a container formed of insulating material and having its inner surface coated with a material forming an anode, said container having a closed end, a terminal in said closed end in engagement with
- said coating, a panel, means for securing said closed end of said container to said panel, a cathode projected into said container, said container having an electrolyte therein, a closure cap supporting said cathode, the outer surface 5 of said container coated with a film of material capable of conducting electricity, said cap in engagement with said coating, said coating in engagement with said panel.
12. An electrolytic condenser, comprising, a 10 container formed of insulating material and having a coating on its inner surface forming an anode, said container having an electrolyte therein, said container having its ends closed, one end thereof having a cap thereon having a copper 15 tube projecting therefrom in said container, and electrical connections to said coating and to said cap.
13. An electrolytic condenser, comprising, a cylindrical container formed of insulating material 20 closed at its ends and having an electrolyte solution therein, the internal wall of said container being coated with material forming a filming anode, one end of said container having a terminal projecting therefrom having engagement with said coating, and a cathode tube extended from the other end of said container into the container, said coating terminating short of the end of the container from which the cathode tube projects. 30
14. An electrolytic condenser, comprising, a container formed of insulating material and having a coating of material on its inner surface forming an anode, said container having an electrolyte therein, a cathode supported in said 35 container, means for supporting said cathode at one end of the container insulated from said coating, a coating on the exterior of said container in contact with said cathode supporting means for carrying the current to the other end 40 of said container, and a terminal at said latter end of the container in engagement with said inner film.
15. In an electrolytic condenser, a container 45 formed of insulating material and having a film of material on its inner wall forming an anode, a terminal at one end of said container in engagement with said film, a cap screwed on the other open end of the container, said cap having a cathode extending therefrom into said container, said container having an electrolyte therein, and said coating terminating short of the closure end of said container, whereby said cathode is insulated from said coating. 50
16. An electrolytic condenser, comprising, a 55 cylindrical body open at both ends, a closure cap on one end of said cylindrical body having a cathode tube extended therefrom, a terminal attached to said cap, said cylindrical body formed of insulating material and having its inner surface 60 coated with a material forming an anode, said material terminating short of said end closed by said cap and extending around the other end of said cylindrical body, a closure cap at the other end of said cylindrical body engaging said coating, and insulating means surrounding said last mentioned cap. 65
